(57) **CLAIM**

The ornamental design for a glass, as shown and described.

DESCRIPTION

FIG. 1 is a perspective view of a glass showing our new design;

FIG. 2 is a side elevational view of the glass of FIG. 1, all sides being the same;

FIG. 3 is a top plan view of the glass of FIG. 1;

FIG. 4 is a bottom plan view of the glass of FIG. 1; and,

FIG. 5 is a cross-sectional view taken along line 5-5 of FIG. 3. More than one side elevational view is omitted because the glass is symmetrical.
